Primary Examiner — Rhea Shields(74) *Attorney, Agent, or Firm* — Platinum Intellectual Property(57) **CLAIM**

The ornamental design for a combined power strip with USB and USB-C ports, as shown and described.

DESCRIPTION

FIG. 1 is a perspective view of a combined power strip with USB and USB-C ports showing the claimed design;

FIG. 2 is a top plan view thereof;

FIG. 3 is a bottom plan view thereof;

FIG. 4 is a first side elevational view thereof;

FIG. 5 is a second side elevational view thereof;

FIG. 6 is a front elevational view thereof; and,

FIG. 7 is a rear elevational view thereof.

In the drawings, the broken lines are for the purpose of illustrating portions of the combined power strip with USB and USB-C ports which form no part of the claimed design.

1 Claim, 7 Drawing Sheets(56)
